UNITED STATES PATENT OFFICE.

EDWARD R. IVES, OF BRIDGEPORT, CONNECTICUT.

DESIGN FOR A TOY-CAP EXPLODER.

SPECIFICATION forming part of Design No. 25,275, dated March 24, 1896.

Application filed February 27, 1896. Serial No. 581,074. Term of patent 7 years.

To all whom it may concern:

Be it known that I, EDWARD R. IVES, a citizen of the United States, residing at Bridgeport, in the county of Fairfield and State of Connecticut, have invented and produced a new and original Design for Toy Cartridge and Cap Exploders; and I do declare the following to be a full, clear, and exact description of the same, reference being had to the accompanying drawing, forming a part thereof.

The figure is an elevation of a toy cartridge and cap exploder illustrating my novel design.

The leading feature of my design consists in the general configuration of the exploder, substantially as hereinafter described.

1 denotes a semicylindrical or rounded base; 2, a shank extending upward therefrom and

provided at its upper end with a ring 3, to which a cord may be attached in use; A, the top piece, which consists of a cylindrical band 4, having hubs 5 extending outward therefrom, and a top 6, having the shape of a truncated cone. The shank passes loosely through the top piece and the latter is retained upon the shank by the ring.

Having thus described my invention, I claim—

The design for a toy cartridge and cap exploder substantially as shown and described.

In testimony whereof I affix my signature in presence of two witnesses.

EDWARD R. IVES.
